UNITED STATES PATENT OFFICE.

JOHN Y. ARNOT, OF OAKLAND, CALIFORNIA.

COMBINED REFRIGERATOR AND FILTER.

No. 856,508.

Specification of Letters Patent.

Patented June 11, 1907.

Application filed June 26, 1905. Serial No. 267,300.

To all whom it may concern:

Be it known that I, JOHN Y. ARNOT, a citizen of the United States, residing at Oakland, in the county of Alameda and State of California, have invented certain new and useful Improvements in a Combined Refrigerator and Filter, of which the following is a specification.

This invention relates to a refrigerator and water cooler, the object of the invention being to provide an apparatus of this character by means of which articles of food may be maintained cool without the use of ice, and which will furthermore afford a supply of filtered drinking water.

In the accompanying drawing, Figure 1 is a front elevation of the apparatus; Fig. 2 is a vertical section thereof; Fig. 3 is a horizontal section on the line A—A of Fig. 1; Fig. 4 is a horizontal section on the line B—B of Fig. 1.

Referring to the drawings, 1 represents a suitable base, preferably rectangular in form, having an upwardly extending flange 2. Upon said base is supported, by blocks 3, a casing or refrigerator 4, having a bottom 5, and side walls 6, preferably made of artificial stone, and a top 7 preferably made of wood. Within the receptacle so formed is a food box 8, also preferably made of artificial stone, supported upon posts 9 of the same material. This box 8 is closed at the top and bottom and on three sides, but opens at the front into the side of the main casing 4 where it is closed by a swinging door 10, of the ordinary construction of an ice box door, having a metallic shell 11 filled with mineral wool or other insulating material 12. Between the box 8 and the top of the refrigerator are four walls or partitions 13 which slope slightly outward from the top of the box to the top of the refrigerator and are formed of porous stone of such nature as to permit water to percolate slowly therethrough. Each wall at the top is formed with a number of small channels 14 to admit of ventilation over the surface of the water, there being thus provided free circulation between the chamber 15 formed by said walls and the remainder of the interior of the casing 4 outside the box 8. The top of this chamber 15 is closed by a cover 16 filled with mineral wool or other suitable material, which cover can be raised by handles 17. In the middle of this lid is a funnel shaped cavity 18 which is closed by a

stopper 19, by removing which water can be poured into the chamber 15. The stopper 19 is centrally perforated to permit the passage of the stem 20 of a float 21, the level of the top of the stem indicating the level of the water in the chamber, and the necessity of replenishing the chamber with water.

The water percolating through the porous walls of the chamber 15 is partly evaporated on the outside of said walls, thereby reducing the temperature of the water, and of the whole interior of the refrigerator, thus enabling articles of food placed in the box to be preserved without the use of ice. The water vapor escaping through the apertures 23, shown in dotted lines. Any excess of water not thus evaporated drops down into the lower portion of the refrigerator whence it can be drawn off from time to time by a faucet 22. This water having passed through the porous walls of the chamber 15 thoroughly filtered, and in fit condition for drinking, can be drawn off through the faucet 22.

This apparatus is of great value in warm climates and in districts far removed from ice houses and in which ice is difficult to obtain, especially where the water is of an inferior quality, as it not only acts as a refrigerator, cooling articles placed therein, but purifies the water furnished as the refrigerating agent.

I claim:

1. An apparatus of the character described, comprising a suitable casing, porous walls within the casing inclosing a water chamber, a food box within the casing the top of which forms the bottom of said chamber, means for supporting said food box at a distance from the interior walls of the casing, said casing being constructed to collect the water filtered through said porous walls, a stopper for closing the aperture to said water chamber, said stopper being centrally perforated, a float having a stem loosely passing through said perforation, and means for drawing off the water filtered through said porous walls, substantially as described.

2. An apparatus of the character described, comprising a suitable casing, porous walls within the casing inclosing a water chamber, a food box within the casing the top of which forms the bottom of said chamber, means for supporting said food box at a distance from the interior walls of the casing, said casing being constructed to collect the water filtered through said porous walls, a centrally perfo-

rated stopper for closing the supply opening to said water chamber, the walls having lateral openings at their tops to permit air to pass therethrough, and means for drawing off the water filtered through said porous walls, substantially as described.

In witness whereof I have hereunto set my

hand in the presence of two subscribing witnesses.

JOHN Y. ARNOT.
